WIRE DRAWING MACHINE

Weld Morgan and Clarke D. Wesson, Worcester, Mass., assignors to Morgan Construction Company, Worcester, Mass., a corporation of Massachusetts.

Application December 23, 1946, Serial No. 717,978

9 Claims. (Cl. 205—14)

1

This invention relates to wire-drawing machines, and more particularly to machines of the continuous type having a plurality of rotatable blocks or drums for drawing wire successively through a series of dies.

It is one object of the invention to provide a continuous wire-drawing machine having an improved means for guiding the wire from each block to the following die, the construction being comparatively light, rigid and inexpensive.

It is a further object of the invention to provide a continuous wire-drawing machine having an improved construction whereby the mechanism which supports and drives the blocks is adequately lubricated and protected against damage from dust and dirt.

It is a further object of the invention to provide a continuous wire-drawing machine having a series of hollow air-cooled blocks, together with a simple and efficient means for conducting air under pressure to the interiors of the blocks.

It is a further object of the invention to provide a continuous wire-drawing machine of the air-cooled type having a new and highly compact arrangement of air supply means in conjunction with the motor which drives the blocks.

It is a further object of the invention to provide a continuous wire-drawing machine having a hollow frame or casing which may be readily constructed primarily from steel plates welded together.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a front elevation of a continuous wire-drawing machine;

Fig. 2 is a top plan view of the machine;

Fig. 3 is an end elevation of the machine;

Fig. 4 is an enlarged view in section taken approximately on the line 4—4 of Fig. 1;

Fig. 5 is a fragmentary section taken on the line 5—5 of Fig. 4;

Fig. 6 is a fragmentary section on a reduced scale taken on the line 6—6 of Fig. 4;

Fig. 7 is an enlarged view in section taken approximately on the line 7—7 of Fig. 2;

Fig. 8 is a section taken on the line 8—8 of Fig. 4;

Fig. 9 is a fragmentary front elevation of the structure shown in Fig. 8; and

2

Fig. 10 is a section taken on the line 10—10 of Fig. 8.

The embodiment illustrated comprises a horizontally elongated hollow rectangular frame or casing 15 having a front wall 16, a rear wall 17, a left end wall 18, a right end wall 19, a bottom wall 20 and a top wall 21. These walls may be formed of steel plates, and except for the top wall they may be connected to one another by welding. 5 The top wall 21 is releasably fastened to the remainder of the frame structure by screws or other suitable means.

A series of intermediate blocks 23 and a finishing block 24 are arranged in a longitudinal row 15 above the top wall 21, all of these blocks being rotatable about vertical axes. A die box 25 is associated with the first block 23, and a die box 26 is associated with each of the other blocks 23 and with the finishing block 24. It will be understood that in known manner each die box supports a die through which wire is drawn by the corresponding block. The die boxes are mounted on the top plate 21, near the front edge thereof, and each of the die boxes 26 is provided with an idler sheave 28 to guide the wire in the proper direction as it approaches the die. The finishing block 24 carries a group of upright pins 29 to support a bundle of finished wire.

The intermediate blocks 23 are arranged to support coils of accumulated wire from which wire is withdrawn upwardly in a generally axial direction and then guided to the following die. For this purpose each block 23 is provided with a group of upright pins 31 and a cap 32 at the top of the pins, this cap being grooved circumferentially to receive a friction ring 33 (Fig. 4) having an eye 34 therein through which the wire is threaded. Directly above each block 23 there is provided an idler sheave 36 (Figs. 1 and 2) over which the wire passes and thence travels downwardly to the corresponding sheave 28. Each sheave 36 is mounted on an upright web 37 with its upper edge welded or otherwise secured to a plate 38 which extends longitudinally of the frame 15 and above the intermediate blocks 23. This plate is bent to curve upwardly and forwardly, as shown in Fig. 3, with its upper surface convex, and it is supported by columns 39 mounted on the rear portion of the frame, the upper portions of the columns being curved to match the curvature of the plate. While only two of these columns 39 appear in Fig. 1, it will be understood that in a long machine having a considerable number of blocks additional columns 55 will be provided. In such case the plate 38 may

be made in a plurality of sections each extending from one column to the next. This transversely curved plate with the upright webs 37 provides a comparatively light beam of great strength and rigidity, so that the sheaves 36 are adequately supported. In order to guide the wire properly on to the sheaves 36, the lower edge of each web 37 is bent laterally to form a flange 41 in which there is mounted a guide bushing 42, these bushings being substantially aligned with the axes of the blocks 23 therebeneath. An upright back plate 43 is mounted on the lower portions of the columns 39 and extends throughout substantially the entire length of the frame 15.

The blocks 23 and 24 are of hollow construction and they are provided with openings 45 and 46 respectively through which air may be discharged into cooling contact with the wire upon the blocks. The air reaches the interior of the blocks through circular openings 47 formed in the top plate 21 of the casing 15, directly beneath the blocks. The air is supplied to the interior of the casing by means of a fan 48 driven by an electric motor 49. This fan is connected to the left end of the casing, adjacent the bottom thereof, by a substantially horizontal duct 50 which is aligned with the casing.

The wire-drawing blocks are supported and driven by a mechanism which is completely enclosed so that it may be properly lubricated and protected against dust and dirt. For this purpose a heavy horizontal bar 52 (Fig. 4) is welded to the rear surface of the front wall 16, somewhat below the top plate 21. A second heavy horizontal bar 53 is provided behind the bar 52 and on the same level, the rear bar 53 being spaced forwardly from the rear wall 17 and connected thereto by a series of web plates 54. As shown in Fig. 6, these plates 54 are inclined downwardly toward the air duct 50 to avoid interference with the air flow and to provide a stronger and better braced construction. The two bars 52 and 53 extend throughout substantially the entire length of the casing 15, and they provide a support for a horizontal plate 56 which bridges across between them. This plate 56 is preferably made in spliced sections, with a separate section for each block, as best shown in Fig. 5. Beneath the plate 56 there is provided a plate 57 (Fig. 4) which is curved transversely to form a trough with one edge higher than the other, the cross-section being J-shaped. The lower edge of this trough is located at the front and is welded or otherwise fastened to the front plate 16. The rear wall of the trough is welded to the bar 53 and to the webs 54. The bottom of the trough is located slightly above the top of the air duct 50. The trough 57 connects at one end (Fig. 5) with the left end wall 18, and it terminates at the other end (Fig. 7) somewhat short of the right end wall 19 to provide space for an oil sump or reservoir 58. The rear wall of this sump is formed by a vertical plate 59 which connects the rear wall of the trough with the wall 19. The left wall of the sump is formed by a transverse vertical plate 60 which connects the adjacent end of the trough with the bottom plate 20. With this construction no air from the fan 48 can reach the sump. The end wall 19 of the casing is provided with a removable plug 62 to permit draining of oil from the sump, and with a filler pipe 63 through which oil may be added to the sump.

Referring now to Fig. 4, it will be seen that the plate 56 is provided with a downwardly extending hollow hub 65 beneath each of the intermediate

blocks 23. This hub may be conveniently made from a heavy tube welded at its upper end to the plate. Within the hub 65 there are mounted upper and lower annular antifriction bearings 66 and 67 respectively which serve to support a vertical shaft 68 having a bevel gear 69 on its lower end. The upper end of the shaft 68 is recessed to receive an antifriction bearing 71 which supports the lower end of a vertical shaft 72. The hub 73 of the block 23 is mounted on the upper portion of the shaft 72. This shaft is supported directly beneath the hub 73 by an antifriction bearing 75 which is mounted in the upper portion of a hollow bracket 76, this bracket having an outwardly extending lower flange 77 which is attached to the plate 56.

A releasable clutch is provided to connect the shafts 68 and 72. For this purpose a clutch member 79 is slidably keyed to the shaft 72 with in the bracket 76, the lower end of this member having teeth thereon for interfitting engagement in a well-known manner with similar teeth on the upper end of the shaft 68. The clutch member 79 is provided with a peripheral groove 80 which is engaged by a shifter fork 81, this fork being keyed to a horizontal shaft 82 rotatably supported in the bracket 76. As best shown in Fig. 8, the front end of the shaft 82 projects forwardly through an annular seal 83 and is connected by a sleeve 84 to an aligned shaft 86. The shaft 86 extends forwardly through the front plate 16 and carries on its front end a crank 87 having a hollow handle 88 thereon. Within this handle there is provided a spring-pressed plunger 90 with a knob 91 on its front end. This plunger is arranged to enter either of two holes 92 in a plate 93 on the front of the casing 15, so that the clutch member 79 may be held in either its engaged position or in its disengaged position as selected.

Referring now to Fig. 7, it will be seen that the plate 56 is provided with a circular opening 95 directly beneath the finishing block 24. Within this opening there is mounted an annular plate 96 having a depending hollow hub 97 which supports an antifriction bearing 98. To the top of the plate 96 there is secured a flanged hollow hub 99 which supports an antifriction bearing 100. A vertical shaft 102 extends through the hubs 97 and 99, and is rotatably supported by the bearings 98 and 100. The finishing block 24 is mounted on the upper end of the shaft 102, and a bevel gear 103 is mounted on the lower end of this shaft.

A common driving means is provided for the bevel gears 69 and 103. For this purpose a horizontal shaft 105 extends longitudinally within the casing 15, directly beneath the vertical shafts 68 and 102. This shaft 105 is rotatably mounted in suitable bearings 106 supported by the trough 57 and the front wall 16. On the shaft 105 there are mounted a series of bevel gears 107 which mesh with the gears 69 and 103 to drive the same, the speed ratios of successive pairs of gears being such as to provide increased speeds for successive blocks. A gear 109 (Fig. 5) is mounted on the shaft 105 near the end thereof adjacent the wall 18, and this gear is driven by a pinion 110 carried by a shaft 111 located behind the shaft 105 and somewhat above the same. The shaft 111 is rotatably supported in bearings 112, and it extends through the end wall 18 to connect with the shaft 114 (Fig. 2) of an electric motor 115. This motor is mounted on the top of the air duct 50.

In order to permit access to the bevel gears for inspection or adjustment, an opening 117 (Fig. 4)

is provided in the wall 16 directly in front of each pair of bevel gears, each opening being closed by a removable plate 18. Access may be had to the air chamber portion of the casing 15 through an opening 19 in the rear wall 17, this opening being closed by a removable plate 21.

Provision is made for lubricating the various gears and bearings. For this purpose a longitudinally extending pipe 123 is mounted beneath the main shaft 105 and supported by suitable straps 124 carried by the bearings 106. The right end of this pipe is connected by a pipe 125 (Fig. 7) to a pump 126 which is mounted on the plate 59. This pump is driven from the shaft 105 through suitable gearing 128. A suction pipe 129 extends downwardly from the pump into the oil sump 58, the lower end of this pipe having a screen 130 thereon. A tube 132 leads from the pump discharge pipe 125 to a pressure gauge 133 mounted on the adjacent end wall 19 of the casing 15. The left end of the pipe 123 connects with a pressure relief valve 134 (Fig. 5) arranged to discharge excess oil into the trough 57. Orifices 136 are provided in the top of the pipe 123, beneath the gear 109 and each of the bevel gears 107, so that jets of oil will be projected upwardly on to these gears. Tubes 138 lead upwardly from the pipe 123 to discharge oil into the upper portions of the brackets 76 and of the hub 99 to lubricate the bearings 75, 71, 66, 67, 98 and 100. Each of these tubes is made in two sections connected by a bulkhead fitting 139 which extends through the plate 56.

For the protection of the operator, a horizontal safety bar 141 is mounted at the front of the casing 15, and a horizontal safety bar 142 is mounted at the right end of the casing. These bars are mechanically connected to suitable limit switches 143 and 144 (Fig. 3) respectively. These limit switches are connected in the circuit of the main drive motor 115 in known manner, so that upon movement of either of the bars 141 or 142 inwardly toward the machine, the motor 115 will be stopped.

The operation of the invention will now be apparent from the above disclosure. The main motor 115 will drive the shaft 111 and the gear 110, which will drive the gear 109 and the shaft 105 with the bevel gears 107 thereon. The gears 107 will drive the gears 69 and 103. With the clutches 79 engaged, each gear 69 will drive the corresponding shafts 68 and 72, and the corresponding intermediate block 23. The gear 103 will drive the shaft 102 and the finishing block 24. The first block 23 will draw wire through the die in the die box 25 to provide an accumulation of wire about the block pins 31. From this accumulation, the wire will travel upwardly through the eye 34 in the friction ring 33 at the top of the block, thence upwardly through the guide 42 thereabove, around the corresponding sheave 36, and then downwardly to the sheave 28 therebeneath, which will direct the wire to the die in the adjacent die box 26. The wire will continue on a similar course through the entire machine until it reaches the finishing block 24, where the finished wire will be coiled upon the pins 29. The machine will be stopped occasionally and a bundle of finished wire will be removed. The speeds of the successive blocks will be so related to the sizes of the successive dies that wire will continue to accumulate slowly on the pins 31 of each intermediate block 23. To reduce the size of the accumulation on a given block the operator need merely stop the rotation of

that particular block and of all the blocks anterior thereto in the series, by disengaging the corresponding clutches 79 through the medium of the handles 88. The main motor 115 is preferably stopped whenever the clutches are operated. When certain of the blocks are stopped, the first rotating block in the series will withdraw wire from the block immediately anterior thereto, the corresponding ring 33 revolving backward in known manner during such withdrawal. The fan 48 will supply air through the duct 50 to the interior of the casing 15, and this air will flow along the casing and upwardly past the angular plates 54, through the openings 47 in the top plate 21 and into the blocks, and thence outwardly through the block openings 45 and 46 into cooling contact with the wire on the blocks.

The sump 58 and the trough 57 will be filled with oil to approximately the level of the center of the pipe 123. The pump 126 will be driven from the shaft 105 through the gearing 128, thereby drawing oil upwardly through the screen 130 and the pipe 129, the oil being delivered under pressure through the pipe 125 to the pipe 123. The oil pressure will be indicated by the gauge 133, and any excess oil will be discharged through the relief valve 134 into the trough 57. Oil will be discharged upwardly in jets from the orifices 136 to lubricate the various gears, and oil will flow upwardly through the tubes 138 to lubricate the bearings for the shafts 68, 72 and 102. The shaft bearings 106 and 112, and the gearing 128 will be lubricated by the oil mist with which the entire oil compartment will be filled by reason of the oil sprays upon various rapidly revolving parts. The oil compartment is completely enclosed and protected from dust and dirt. The oil will return to the trough 57 and flow along this trough back to the sump 58. The lower surface of the trough is fully exposed to the current of air flowing through the casing, and as a result the trough and the oil therein will be effectively cooled.

The curved plate 38 and the upright webs 37 form a light and inexpensive yet strong and rigid beam which supports the sheaves 36 in a proper manner. Since the air duct 50 is aligned with the casing 15, and the main motor 115 is positioned above the air duct, the machine is well adapted for installation parallel with other similar machines. Such an arrangement will be economical of floor space, and the aisles between the machines will be unobstructed. Since the main motor 115 and the fan motor 49 are located at the same end of the machine, the electrical wiring will be simplified.

Having thus described our invention, what we claim as new and desire to secure by Letters Patent is:

1. An apparatus for use in a wire-drawing machine of the type having a horizontally elongated frame and a series of blocks arranged along the top of the frame and rotatable about vertical axes, the said apparatus comprising a plurality of upright columns, a transversely curved plate supported by the columns with its upper surface convex, spaced upright webs secured to the lower surface of the plate, and wire-guiding idler sheaves mounted on the said webs and adapted to receive wire as it travels upwardly from the blocks.

2. A supporting and driving mechanism for a rotatable wire-drawing block, the said mechanism comprising a substantially horizontal plate provided with a hollow vertical hub, two verti-

ally spaced annular bearings mounted within the hub, a vertical drive shaft rotatably supported by the bearings and having a recess in its upper end, a hollow bracket secured to the plate above the hub, a vertical block shaft extending upwardly through the bracket, an annular bearing for the lower end of the block shaft mounted within the said recess, an annular bearing for the intermediate portion of the block shaft mounted in the bracket, a clutch member slidably and non-rotatably mounted on the block shaft immediately above the drive shaft, the lower end of the clutch member and the upper end of the drive shaft having interengaging parts, and manually operable means to slide the clutch member upwardly along the block shaft and thereby separate the said parts.

3. A horizontally elongated frame for a wire-drawing machine of the type having a horizontal row of hollow blocks rotatable about vertical axes and provided with apertures for the discharge of air into contact with wire wound about the blocks, the said frame comprising an upright front wall, an upright rear wall, a generally horizontal bottom wall, a generally horizontal top wall having a series of openings therein adapted to deliver air to blocks thereabove, two upright end walls one of which has an opening therein immediately above the bottom wall for the admission of air, and walls forming a horizontally elongated compartment adapted to enclose driving mechanism for the blocks, the compartment being spaced an appreciable distance downwardly from the top wall, forwardly from the rear wall and upwardly from the bottom wall, the said front wall forming the front wall of the compartment, and the construction being such that air introduced through the air admission opening will flow longitudinally beneath the compartment and upwardly between the compartment and the rear wall to the openings in the top wall.

4. Apparatus as set forth in claim 3, in which the rear wall is connected to the rear wall of the

compartment by a series of plates which are spaced from one another to allow air to flow upwardly between them.

5. Apparatus as set forth in claim 4, in which
5 the plates are inclined downwardly toward the
air admission opening.

6. Apparatus as set forth in claim 3, in which the rear wall of the compartment and the bottom wall thereof are formed by a plate of substantially J-shape in cross-section.

7. Apparatus as set forth in claim 3, in which an oil reservoir is provided below the compartment.

ment and in communication with the end thereof opposite the air admission opening.

8. Apparatus as set forth in claim 3, in which a horizontal air duct is connected to the air admission opening, and a motor for the actuation of the driving mechanism is mounted above the air duct.

20 9. Apparatus as set forth in claim 3, in which
the upper wall of the compartment is formed by
a substantially horizontal plate which is sup-
ported at its front and rear edges respectively
by two parallel horizontal bars, one bar being
25 secured to the front wall and the other bar being
spaced forwardly from the rear wall and con-
nected thereto by supporting means.
